UNITED STATES PATENT OFFICE

OSCAR S. FIELD, OF ALBANY, NEW YORK, ASSIGNOR TO GENERAL RAILWAY SIGNAL COMPANY, OF ROCHESTER, NEW YORK

LIGHT SIGNAL

Application filed August 10, 1926. Serial No. 128,437.

This invention relates to new improvements in light signalling apparatus.

One object is to provide a signal which is extremely compact and which has a high degree of accessibility to its operating parts. A further object is to provide an operating means for the signal which will have a minimum possibility of mechanical sticking, together with the characteristic of being readily inspected at any time without completely taking the mechanism apart. A further object is to provide a signal which is of unit construction whereby various parts may be replaced or exchanged as may be necessary, thereby readily facilitating the maintenance of the apparatus. With these and other objects in view as may be more readily apparent from the following specification and appended claims, I will now proceed to describe one embodiment of my invention. In the drawings:—

Figure 1 is a cross section through a mechanism according to this invention. Figure 2 is a transverse section through the mechanism. Figure 3 is an isometric projection of the iron structure employed in the mechanism showing both the field structure and armature structure. Figure 4 is a detail of the bell crank adjustment.

The basic principle of the signal, which comprises the utilization of a source of light together with means for concentrating said source through a second focal point, passing this light through a screen through this focal point and then projecting the same from a lens, is old in the art. The present invention consists more particularly of improved methods of construction and combination of the apparatus rather than in the basic light projection idea.

The optical principle above referred to in this embodiment comprises a source of light 1 in combination with an elliptical reflector 2 which is adapted to collect and concentrate the rays from the source of light 1 to a focal point 3. At this focal point colored spectacles or other screens 4 are movably mounted and have the effect of changing the color or beam characteristic in accordance with the particular screen then intercepting the beam. The

beam then diverges to cover a lens which is adapted to project the rays in a substantially parallel beam. In the present embodiment of the invention the source of light 1 and reflector 2 are carried in a holder 7 which is mounted in the cover 8 of the mechanism case 9, thereby making this part of the signal removable with the mechanism.

The interior mechanism 40 comprises a mechanism case 9 equipped with a suitable cover 8 mounted thereon by means of screws 68. The mechanism proper comprises a three position motor element having a polarizing field structure together with a movable armature. The field structure consists of two pole pieces or pole shoes 69 and 70, made of suitable flux conductive material. These pole shoes are connected together by means of a core 71 adapted to pass through apertures 72 in the pole shoes 69 and 70, and being provided with a taper thread and plug 73 at either end. The ends are suitably split as indicated at 74 whereby upon tightening of the taper plugs 73 the ends of the core will be expanded to tightly fit the holes 72. Upon the core 71 a suitable field excitation winding 75 is provided. From the above description it will be apparent that upon energization of the coil 75, the pole shoes will assume opposite polarities. This constitutes the field structure of the mechanism.

The armature structure consists of a suitable core 76 preferably made of Norway iron and equipped with polar vanes 77 and 78 respectively adapted to coact with the pole shoes 69 and 70. These vanes are mounted on the core 76 by means of clamping nuts 78a. The core 76 is provided with a suitable energizing winding 79 which is carried in a bakelite shell 80 adapted to insulate the coil and to properly support it in such a manner that it will not come into physical contact with the core 76. The method of support of the bakelite shell 80 is by means of suitable lugs 81 formed on the bakelite shell and adapted to be carried in the notches 82 formed in the pole shoes 69 and 70.

In order to properly support the armature structure front and rear bracket castings 83 and 84 are provided. These brackets are

mounted on the pole shoes 69 and 70 by means of suitable studs 85 and clamping nuts 86, said studs passing through the brackets 83 and 84 and the holes 87 in the pole shoes 69 and 70. In order to compensate for slight variations in manufacture deformed washers 88 of suitable spring material are placed on the studs between the pole shoes and the rear bracket 84 thereby taking up any variation in these parts. The rear bracket 84 also forms the supporting bracket for the mechanism in the case and for this purpose is provided with extending lugs 89 through which screws 90 pass into the case 9. The bracket 84 is 10 suitably insulated from the case 9 by means of insulating bushings 91 and washers 92.

At either end of the core 76 shaft extensions 93 and 94 are provided, having properly turned ends 95 and 96 adapted to roll in ball 20 bearings 97 and 98. The shaft ends 95 and 96 respectively are adapted to roll directly on the balls 99 and the end thrust is taken between the balls 99 and the shoulders 100. The bearings are adapted to be held in the 25 brackets 83 and 84 by means of suitable locking screws 101 which are equipped with an enlarged head forming shoulders 102 adapted to engage with the raceway element 103 of the ball bearing, thereby locking this element 30 to its respective bracket. The rear end 104 of the bearing is held in place by means of locking nuts 105 adapted to be threaded on the large section 106 of the screws 101. This construction allows for the removal of member 104 from the bearing at any time so that 35 the bearing may be inspected for wear and cleanliness. The polar vane 78 is equipped with the spectacle carrying member 107 adapted to carry spectacles 4 suitably mounted thereon by means of spring clips 108 and 40 coacting clips 109. These spectacles can be of any suitable material or color that may be found desirable, it being the specific purpose to change the characteristic of the beam passing through them in accordance with the particular spectacle presented at the focal point. In the present embodiment of the invention 45 three of these spectacles are provided for normal signal work, these being made of red, yellow, and green glass respectively, the red glass being placed in the central position so that it will be coincident with the axis of the light beam when the mechanism is in the deenergized or neutral position.

50 The front end of the armature structure is provided with a roller carrying member 110 suitably mounted on polar vane 77 by means of rivets 111. This member is equipped with suitable hardened rollers 112 carried at the 55 extremities of miniature bell cranks 113 which in their turn are pivoted at 114 to the member 110. The purpose of the bell cranks 113 is to provide means whereby the distance between the centers of the rollers 112 and the 60 center of the axis of rotation of the arma-

ture structure may be slightly varied, thereby giving some adjustment to the mechanism. The bell cranks, after being properly set are locked in place by means of a locking screw 115. In order to prevent excessive adjustment being made at this point extending ears 70 116 are provided on the bell cranks 113 which are adapted to engage the locking screw 115 and thereby limit the motion of the crank. The motion of the crank is limited in the 75 reverse direction by the shaft member 93.

Coacting with the rollers 112 counter weights 117 and 118 are provided. These counter weights are hinged at 119 and 120 in front bracket casting 83 and are provided with extending ears 121 and 122 adapted to engage with the rollers 112. In order to properly centralize the mechanism adjustable stop screws 123 are provided in the front bracket casting 83 in such a location that they are adapted to engage with the underside of the counter weights 117 and 118 and thereby limit or modify the length of movement of the counter weights. By means of 80 this adjustment the mechanism may be caused to properly center, bringing the central spectacle giving the red indication in coincidence with the light beam, due to the gravitational effect of the weights 117 and 118 acting upon the rollers 112. The armature assembly is further provided with a counter weight 110a which is adapted to compensate for the weight of the spectacles 4 and spectacle carrying member 107 and to cause a slight bias of the armature assembly 85 to the neutral or deenergized position as shown in the figures. In order to properly limit the movement of the armature in either direction so that the other spectacles may properly coincide with the light axis upon 90 energization of the mechanism, adjustable stops 124 are provided. These are adapted to engage with extending ears 125 on the member 110 of the armature assembly. In order to absorb any tendency of the armature assembly to rebound from the stops 124 when the mechanism is energized a fly wheel 94a is 95 loosely mounted upon the shaft extension 94 and is adapted to be held in frictional engagement with shoulder 95a by means of a compression spring 96a. This spring is held in place on shaft extension 94 by means of a collar 97a pinned to said shaft. When the ear 125 on the armature assembly strikes the 100 stop 124 the fly wheel 94 will slip slightly and thereby absorb the energy of rebound.

The under side of the counter weights 117 and 118 may be suitably provided with insulating buttons 126 adapted to carry contact fingers 127. These contact fingers are so arranged that they will suitably coact with front and back contacts 128 and 129 respectively. Said front and back contacts are carried by means of a bar 130 of insulating material suitably mounted to the pole shoes 69 110 115 120 125 130

and 70 by means of screws 131. Terminal posts 132 are provided for the contacts and contact fingers, the finger being electrically connected to its terminal by means of a flexible pigtail 133 of conducting material. A panel 134 of suitable insulating material is provided on the outside of mechanism case 9 whereby all electrical connections to the mechanism may be made to outside terminal posts 135 carried by panel 134 as shown more particularly in Figures 1, 2, and 4. The terminal posts 135 will, of course, be electrically connected by suitable wiring, not shown, to the various coils and contacts on the inside of the mechanism.

The case 9 is provided with an aperture 136 equipped with a plate glass cover 137 through which the rays of light emitted from the source 1 may pass. The cover 8 of the mechanism case is provided with an aperture 138 properly equipped with an inspection glass 139 whereby the mechanism may be seen and the contacts inspected without removal of this cover. Formed in the cover 8 is a recess or well 140 properly equipped with a sealing glass 141 which is adapted to complete the closure of the mechanism case. The reflector and light carrying member 7 is adapted to fit snugly in the well 140 as shown at 142 thereby aligning the reflector and light assembly with the axis of the signal. The member 7 is provided with suitable studs 143 arranged in triangular formation. Upon these studs a plate 144 is mounted by means of adjusting nuts 145 in such a way that the plate 144 may be moved longitudinally on the studs in equal or varying degrees thereby enabling the source of light 1 to be placed at the correct focal point of the reflector 2. The plate 144 is adapted to carry an insulating member 145a to which is attached a socket collar 146 adapted to support the base of bulb 147. The member 145a is further provided with a spring pressed stud 148 adapted to make electrical contact with the center contact of the bulb 147.

In order to make the reflector assembly readily removable from the signal mechanism it is arranged to hold it in place by means of spring clips 150 suitably attached to the cover 8 by means of rivets 151. Slots 152 are provided in the rear of member 7 whereby the member may be slipped into place, then rotated as indicated by the arrow in Figure 2, whereupon the spring end 153 will pass over a hump 154 formed on member 7 dropping into a notch formed thereon thereby locking the reflector assembly in place.

The operation of the mechanism is as follows: The field coil 75 is continuously energized, this forming the polarizing feature of the mechanism. In view of the balanced structure employed, this will not develop any torque to cause the armature to rotate. How-

ever, upon energization of the armature coil 79 the vanes of the armature will be caused to react against the pole shoes thereby causing the armature to rotate in a clockwise or counter clockwise direction in accordance with the relative polarity of the armature current, thereby moving the respective spectacles into the axis of the light beam. It will be noted that in order to obtain a maximum torque and to obtain a straight line torque characteristic as nearly as possible the curvature 155 on the pole shoes 69 and 70 is not concentric with the axis of rotation but is deformed whereby the distance from the axis to the pole shoe increases as we approach the tips of the pole shoes. This formation has the effect of decreasing the torque somewhat at the commencement of the stroke and increasing the torque at the completion of the stroke, thereby giving more desirable operating results.

While I have described one embodiment of the invention, it is well understood that many departures can be made from the specific details of the structure without departing from the spirit of the invention.

What I claim as new is:—

1. In a translating device for relays, light signals, and the like, a field structure having oppositely disposed parallel pole faces, a core in said field structure, tapered threaded plugs in the ends of said core to expand said core ends to securely unite said field structure and reduce air gap losses, and an armature structure comprising a horizontal core, and oscillable plane vanes on said core arranged to coact with said pole faces to be operated to either of two extreme positions.

2. In a translating device, in combination, a field structure, an armature, a spindle mounting said armature to rock from a neutral to an extreme position, an eccentric pin on said armature, means cooperating with said pin to bias said armature toward said neutral position, and friction energy absorbing means for absorbing energy of movement of said spindle to prevent bobbing of said spindle.

3. In a translating device, in combination, a field structure, an armature, a spindle mounting said armature to rock from a neutral to an extreme position, an eccentric pin on said armature, means for adjusting the position of said pin and then fixing it in adjusted position, means cooperating with said pin to bias said armature toward said neutral position, and friction energy absorbing means including a fly wheel resiliently mounted on said spindle for absorbing energy of movement of said spindle to prevent bobbing of said spindle.

4. In a translating device, a field structure having oppositely disposed parallel plane pole faces, an armature structure operable to either of two extreme positions and compris-

- ing, a horizontal core, oscillable plane vanes on said core parallel with, and arranged to coact with, said pole faces, and eccentric pins on cranks adjustably carried on said armature, and counter weighting means bearing against said pins to return the armature from an extreme to a neutral position. 70
5. In a translating device, a field structure, an armature rockable to either of two extreme positions and comprising a horizontal core, oscillable vanes on said core positioned to coact with said field structure, adjustable counterweighting means arranged to return the armature structure from an extreme to a neutral position, and friction fly wheel means associated with said core to absorb energy and prevent bobbing when said armature is rocked to either extreme position. 75
- 10 6. In a translating device, a field structure, an armature structure comprising, a horizontal core, oscillable vanes on said core adapted to coact with said field structure to be operated to either of two extreme positions, ball bearings for said armature structure, removable ends to said bearings for inspection and cleaning, adjustable biasing means for said core to return it from an extreme position, and friction energy absorbing means for said core to prevent bobbing when operated to an extreme position. 80
- 15 7. In a relay, in combination, a field structure including spaced parallel field plates, magnetizing means for the field plates, a pivoted armature core substantially at right angles to said field plates, spaced armature plates carried by the core and substantially parallel with said field plates, and magnetizing means for the armature plates, whereby oscillation of the armature plates in planes parallel with said field plates rocks the armature core. 85
- 20 8. In a relay, in combination, a field structure including spaced parallel field plates, magnetizing means for the field plates, a pivoted armature core substantially at right angles to said field plates, spaced armature plates carried by the core and substantially parallel with said field plates, and magnetizing means for the armature plates, whereby oscillation of the armature plates in planes parallel with said field plates rocks the armature core, said field plates being cut out around the armature core to space the cut out edges non-concentrically from the core, whereby to improve the torque characteristics of the relay. 90
- 25 9. In a relay, in combination, a field structure in the form of an open ended box, a slot in each of two opposite sides of the box, a pivoted armature core passing through the slots, a plate like vane carried by the core at each end and parallel with the slotted sides of the box, and means for energizing the field structure and the armature structure. 95
- 30 10. In a relay, in combination, a field structure in the form of an open ended box, a slot in each of two opposite sides of the box, a pivoted armature core passing through the slots, a plate like vane carried by the core at each end and parallel with the slotted sides of the box, and means for energizing the field structure and the armature structure. 100
- 35 11. In a relay, in combination, a field structure in the form of an open ended box, a slot in each of two opposite sides of the box, a pivoted armature core passing through the slots, a plate like vane carried by the core at each end and parallel with the slotted sides of the box, and means for energizing the field structure and the armature structure, the armature vanes being angularly displaced substantially 180° on the core, whereby to make the torque on the core, due to coaction between the vanes and the slotted sides of the box, additive. 105
- 40 12. In a relay, in combination, a field structure in the form of an open ended box, a slot in each of two opposite sides of the box, a pivoted armature core passing through the slots, a plate like vane carried by the core and parallel with the slotted sides of the box, and means for energizing the field structure and the armature structure, the slots in the sides of the box being curved and spacing the cut edges of the sides eccentrically to the armature core, whereby to improve the torque characteristics of the relay. 110
- 45 In testimony whereof, I have signed my name to this specification. 115
